(57) **CLAIM**

The ornamental design for a double drawer box, as shown and described.

DESCRIPTION

FIG. 1 is a perspective view of the double drawer box of the present invention as a whole.

FIG. 2 is a top view of the double drawer box of the present invention.

FIG. 3 is a front view of the double drawer box of the present invention, the rear view being a mirror image thereof.

FIG. 4 is a right side view of the double drawer box of the present invention, the left side view being a mirror image thereof.

FIG. 5 is a perspective view of the crossbeam of the double drawer box of the present invention, shown separately for completeness of illustration.

FIG. 6 is an enlarged perspective view of one side wall of the double drawer box of the present invention, shown separately for completeness of illustration; and,

FIG. 7 is an enlarged perspective view of the one side wall shown in FIG. 6 from the opposite direction shown in FIG. 6.
